Primary Examiner — Kevin K Rudzinski*Assistant Examiner* — Clare Ann Gannon(74) *Attorney, Agent, or Firm* — Lucas & Mercanti, LLP(57) **CLAIM**

The ornamental design for a shoe, as shown and described.

DESCRIPTION

FIG. 1 is a perspective view of a shoe according to the design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines on the surface of the shoe and periphery represent stitching and form a part of the claim. The broken lines inside the shoe form no part of the claimed design.
